UNITED STATES PATENT OFFICE.

ELIJAH H. CROOKER, OF BOSTON, MASSACHUSETTS.

IMPROVEMENT IN FOOTSTOOLS.

Specification forming part of Letters Patent No. **158,250**, dated December 29, 1874; application filed April 1, 1874.

To all whom it may concern:

Be it known that I, ELIJAH H. CROOKER, of Boston, in the county of Suffolk and State of Massachusetts, have invented a new and valuable Improvement in Footstools, of which the following, when taken in connection with the accompanying drawings, is a full, clear, and exact specification:

In this invention the support for the feet is suspended between two uprights, and is capable of being raised or lowered at pleasure, remaining, however, perfectly firm and immovable in any position.

The invention, which consists of an arrangement for raising, lowering, and holding in place the said foot-support, is described in detail below.

In the accompanying illustrations, Figure 1 is an elevation of a footstool embodying my invention. Fig. 2 is a vertical section of the same. Fig. 3 is a plan of the disk. Fig. 4 is a detail sectional view.

Similar letters of reference indicate corresponding parts.

a a are two uprights, kept together at the bottom by the rounds or stretchers *b b*. *c* is the support for the feet, suspended between the uprights *a a* by means of the cord, chain, or equivalent, *d*, which is suspended or hung in grooves *e'*, cut in the inner sides of the uprights *a a*, and passes under the support *c*. Metallic slides *e e*, attached to the support *c*, and sliding in the grooves *e'*, prevent the said support from tipping. *f f* are brass plates screwed to the inner sides of the uprights *a a*, and having openings *h*, (see Fig. 4,) through which the stretcher or round *k* passes. One or both of the openings *h* are made somewhat elongated, so as to allow the stretcher *k* to be slightly lifted. *g* is a pin, fixed in one of the

plates *f*, made flush with its surface, and projecting into an upright, *a*. *m* is a disk-wheel, having notches *m'* at intervals around its rim, and rotating with the round *k*. *n* is the spindle, around which the cord *d* winds, and *o* is a rotating disk.

In practical operation, my footstool works as follows: When the foot-support *c* is to be raised or lowered, the end of the stretcher *k* nearest the pin *g* is raised a little in the opening *h*, assuming the position represented in Fig. 4. The said stretcher is then rotated in either direction, and the cord *d* winds or unwinds. When the support *c* has arrived at the desired position, the stretcher *k* is simply released, and it drops into its former position in the opening *h*, the disk *m m'* drops upon the pin *g*, and the said pin slips into the first notch *m'*, and the support *c* is thus held in place.

The parts *a b c k* may be made very ornamental, thus producing a handsome article of furniture.

The above-described arrangement for raising, depressing, and retaining in place the footstool *c* is simple, not expensive, and easily operated, as any child who can rotate the stretcher *k* can adjust the stool at will.

Having thus fully described my invention, I do not claim as new an adjustable foot-rest suspended between two uprights; but

What I claim, and desire to secure by Letters Patent, is—

The combination of the stretcher *k* and spindles *n* with the plates *f*, pin *g*, and wheel *m m'*, substantially as and for the purposes described.

ELIJAH H. CROOKER.
